Philip Libson, Brooklyn, N. Y., assignor to Helena Rubinstein, Inc., New York, N. Y., a corporation of New York

Application June 14, 1949, Serial No. 3,275

Term of patent 14 years

(Cl. D86—10)

To all whom it may concern:

Be it known that I, Philip Libson, a citizen of United States of America, residing at 2021 East 17th Street, Brooklyn, in the county of Kings and State of New York, have invented a new, original, and ornamental Design for a Lipstick Holder Casing, of which the following is a specification, reference being had to the accompanying drawing, forming part thereof.

In the drawing

Fig. 1 is a top plan view of a lipstick holder casing, showing my new design;

Fig. 2 is a front elevational view of the same,

Fig. 3 is a rear elevational view of the casing,

Fig. 4 is an end elevational view of the same.

I claim:

The ornamental design for a lipstick holder casing, as shown.

PHILIP LIBSON.
